UNITED STATES PATENT OFFICE.

CYRUS CHAMBERS, JR., OF PHILADELPHIA, PENNSYLVANIA.

PAPER-FOLDING MACHINE.

Specification forming part of Letters Patent No. 23,445, dated April 5, 1859; Reissued July 21, 1874, No. 5,974.

To all whom it may concern:

Be it known that I, CYRUS CHAMBERS, Jr., of the city and county of Philadelphia and State of Pennsylvania, have invented certain new and useful Improvements in Paper-Folding Machines; and I do hereby declare the following to be a full, clear, and exact description of the same, reference being had to the accompanying drawings and to the letters of reference marked thereon.

My invention relates to improvements in paper folding machines, for which Letters Patent of the United States were granted to me on the 7th day of October, 1856, and on the 3rd day of November, 1857; and my improvements consist, first, in register pins, so constructed and so attached to a paper folding machine, that they will retain their proper position for entering the holes in the sheet, for the adjustment of the latter, and yield by the movement of the same in the manner described hereafter. Second, in adjusting one of the register pins laterally and longitudinally, independently of the other pin, by means of the slides hereinafter described, or their equivalents. Third, in adjusting both pins simultaneously, both laterally and longitudinally by means of frames, hereinafter described, or their equivalents, one frame being adjustable in one direction on the other frame, and the latter, together with the former, being adjustable in another direction on the frame of the machine, or any attachment thereto. Fourth, in any convenient number of rods, terminating at one of the folding rollers, the ends of the said rods passing into grooves in the said rollers, as and for the purpose herein-after set forth. Fifth, in an adjustable stop, with its inner edge of a curved or angular form, or otherwise so constructed that the ends only of the folded edge of the sheet shall be in contact with the said stop, for the purpose hereafter specified. Sixth, in a combination of a plunger and two adjustable plates, the said plates being arranged substantially as and for the purpose hereinafter set forth. Seventh, in two curved wires or their equivalents, attached to the machine in the manner described hereafter, and for the purpose specified. Eighth, in a combination of an alarm or indicating apparatus

with a paper folding machine, when the said indicator is operated by a sheet folded by the said machine. Ninth, in causing a sliding board, against which the sheets are packed in the folding trough, to move along the latter with a diminution of friction as the sheets accumulate, by means of springs attached to the said board, and arranged to bear against wedgeformed or inclined strips in the manner hereafter described.

In order to enable others to make and use my invention, I will now proceed to describe its construction and operation.

On reference to the accompanying drawing, which forms a part of this specification, Figure 1, is a side elevation of a paper folding machine with my improvements. Fig. 2, a sectional elevation. Fig. 3, an end view, looking in the direction of the arrow, Fig. 1. Fig. 4, a ground plan. Figs. 5 and 6, enlarged sectional views of the registering device. Fig. 7, a plan of Figs. 5 and 6. Figs. 8 and 9, detached views, illustrating part of the packing arrangement. Fig. 10, a perspective view of the device for changing the position of the folded sheets, prior to their being deposited in the packing trough.

Similar letters refer to similar parts throughout the several views.

A and A' are the opposite side frames of the machine and are connected together by the upper transverse bars B, C and D, and lower bars E and F (Fig. 2).

G is the main driving shaft of the machine, and on this shaft is secured a pulley H, on the back of which is a cam a, both being situated outside the frame. To the same shaft G are also secured an eccentric I, a cam J and another cam K.

The several duties of the above mentioned parts and the manner in which they are accomplished will be fully set forth hereafter.

To the top of the opposite frames A and A' are secured suitable boxes, in which turn the journals of the first pair of folding rollers L and L', the journal of the roller L projecting beyond the frame, and the projecting end being furnished with a pulley, driven by a band or cord from the main pulley H of the driving shaft G. To the opposite frames are also attached two boxes for the shaft M, to which is secured an arm N, and,

on the end of the latter is a metal plate *f*, the edge of which, when depressed, coincides with the point of contact of the two rollers *L* and *L'* with each other, as best observed in Fig. 6. The arm *N* is operated by the cam *a* at the back of the pulley *H*, the said cam bearing against a roller on the end of the arm *b*, the latter being secured to the shaft *M*.
 10 P and *P'* (Figs. 2 and 4) are the second pair of rollers, caused to revolve in boxes, secured to the cross bars *B* and *C* of the frame, by any suitable system of gearing. A blade on an arm *Q* coincides, when depressed, with the point of contact of these two rollers, the arm being secured to a shaft *q*, which turns in bearings attached to the inside of the frame *A'*, an arm on this shaft being operated by the cam *K* on the driving shaft *G*.

R and *R'* are the third pair of folding rollers, placed at right angles to the second pair, and turning in boxes attached to the frame. A blade on the end of the arm *S* coincides, when depressed, with the point of contact of the two rollers, and this arm is secured to a shaft *T*, which turns in boxes on the transverse bar *B* of the frame, an arm *U* on the said shaft being operated by the cam *J* on the driving shaft *G*.

V and *V'* are the fourth and last pair of folding rollers, hung to the frame of the machine, and turned by any suitable system of gearing. Above these rollers is a blade on the end of the arm *W*, which is secured to the shaft *q*, the latter being, as before described, operated by the cam *K* on the driving shaft *G*.

The system of tapes or bands, used in connection with the above described rollers, are similar and similarly arranged to those described in my patent, granted October 7th, 1856.

Two pins *e* and *e'* are situated one on each side of the first pair of rollers *L* and *L'*. Each pin is secured to a spindle, the pin *e* to the spindle *m*, and the pin *e'* to the pin *m'*, see Fig. 7. The spindle *m* turns in a bracket *n* secured to a bar *p*, which forms a part of the frame *X*. The spindle *m'* turns in a bracket *n'*, which is arranged to slide transversely with the machine in a block *n''*, the latter being arranged to slide longitudinally with the machine in a projection *p'* on the bar *p''*, which also forms a part of the frame *X*. A projection *p''* from this frame is arranged to slide longitudinally in a projection on the bar *Y*, the opposite ends of which rest on and are so secured to the opposite frames *A* and *A'* of the machine, that the bar can be readily adjusted transversely, but can have no movement in the direction of the length of the machine. It will now be seen, that the entire frame *X*, with its register pins *e* and *e'*, may be ad-

justed both laterally and longitudinally, and their position, in respect to the rollers, altered at pleasure. The positions of the pins, too, in respect to each other, can be readily adjusted laterally and longitudinally, by the arrangement of slides, already described as being connected with the spindle *m'*. Each of the spindles *m* and *m'* has a spiral spring coiled around it, one end of the spring being attached to the bracket in which the spindle turns, and the other end to the spindle itself. The tendency of the spiral springs is to maintain the register pins in the vertical position shown in Fig. 5, beyond which they are prevented from moving outward by a pin projecting from the spindle, and bearing against the bracket in which it turns, or by any other suitable device. The register pins, however, can be depressed, so as to move toward the rollers, as seen in Fig. 6, but instantly recover their vertical position, on the removal of the force by which they were depressed.

It will be observed, on reference to Figs. 4 and 7, that the roller *L'* has three grooves *l*, *l*, *l*, and that into each groove projects one of the rods 1, 2 and 3, which at one end are secured to the transverse bar *B* of the frame, and at the opposite end to a cross bar *c*. The ends of the rods terminate at or near a line drawn perpendicularly through the center of the roller *L'*, the under sides of the rods being level or thereabout with the underside of the roller.

On the rods 1, 2 and 3 is an adjustable bar *Z* (Fig. 4), which forms the stop for the sheet of paper, after it has received its first fold. The inner face of this bar, against which the folded edge of the sheet is brought in contact, is not straight, but of such a curved or angular form, that its surface at the ends is nearer to the rollers than the surface at the middle.

O is the packing trough, the opposite ends of which are secured to the frame of the machine, and which is of the angular form, represented in the enlarged sectional view Fig. 8. In the trough is a sliding board *O'* (Figs. 1 and 2), to which are secured two springs 4, one spring overlapping one side, and the other overlapping the opposite side of the trough, and each spring bearing against a strip 5, secured to each side. Each strip represents a wedge, increasing in thickness from the outer end of the trough to the point where it terminates. The springs 4 bearing against these wedges formed on inclined strips, tend by their friction to retard the movement of the sliding board *O'*, and, as the friction must be greater where the thickest portion of the strips presents itself, than at the end of the trough where the strips are thinner, the board will move more readily in the trough near the end than about its middle. Another board or plun-

ger C is also arranged to slide in the trough, a projection from the board passing through a slot in the trough, and the projection being connected by means of a rod to the 5 lower end of the arm 7, which is hung loosely to lugs on the underside of the transverse bar D of the frame. To this arm is connected one end of the rod I', the opposite end of which embraces the eccentric I on the 10 driving shaft G, the revolving motion of the latter consequently imparting a vibrating motion to the arm 7 and a reciprocating motion to the plunger C. The latter has an adjustable plate 8, which can be raised and 15 lowered at pleasure, and which will be more particularly alluded to hereafter. To a permanent part of the frame is also attached a plate 9 (Figs. 1, 2, and 8), the plate being so arranged as to be readily raised and 20 lowered, for an object which will be apparent hereafter. A tongue 10 (Fig. 8), which is secured to or forms a part of the spindle 11, projects through an opening in the trough, the spindle 11 turning in a 25 bracket 12, secured to the underside of the trough. A spiral spring surrounds the spindle and tends to maintain the tongue 10 in a vertical position with its point projecting a short distance into the trough, when 30 not depressed by the edge of the folded sheet, as described hereafter. A pin 13, projecting from the spindle 11, may be attached to any suitable registering or alarm apparatus, for indicating the number of sheets 35 which have been perfectly folded.

Immediately under the last pair of folding rollers V and V', and to a permanent part of the frame, is secured a bent bracket 14, the form of which will be best observed 40 on reference to Fig. 10. From this bracket, and immediately over the trough, project two wires 15 and 16, which are bent in a peculiar form, and the object of which will be fully set forth hereafter.

45 It should be understood that the machine is covered at the top with a flat plate for receiving the sheet to be folded, the register pins projecting above this plate, in which is an opening for the play of the blade on the arm N. Before the machine is started, the register pins are adjusted to suit the holes made in the paper during the process 50 of printing. This may be readily accomplished by adjusting the frame X on the bar Y, by adjusting the latter on the main frame, as well as by adjusting the latter on the projection p' of the frame X. Ample means are thus afforded for altering the 55 position of the register pins, in respect to the first pair of folding rollers, as well as in respect to each other. The stopping rod 2 must also be adjusted to a proper position, before the machine is put in operation. On 60 turning the driving shaft G, a revolving

motion toward each other will be imparted to each of the four pairs of folding rollers, and a reciprocating motion to the blades, by which the paper is forced between the rollers, as described in my former patent of October 7, 1856. At the same time, a reciprocating motion will be imparted to the plunger C, in the trough O. The sheet of paper to be folded being placed by the operator on the cover of the machine in such a position, that the register pins e and e' shall fit into the holes made in the paper during the process of printing, the blade f on the arm N, which is furnished with needle points, descends suddenly onto the sheet, 75 creases the latter, and forces the creased edge between the first pair of folding rollers L and L'. As the blade is in the act of creasing the paper, the two ends of the latter must be drawn toward each other, and, consequently, the register pins e and e', were 80 they to remain in their vertical position, would be the means of tearing the paper, so as to render it unfit for use. The spiral springs, however, which surround the spindles m and m' to which the pins are attached, 85 are of such delicacy, that, while they tend to maintain the pins in a vertical position, the latter will instantly fall down, as seen in Fig. 6, by the mere movement of the paper, and unaided by any mechanical appliances. As the pins fall to this position, 90 they leave the holes in the paper, and, as the latter, by the action of the rollers, is being folded, the paper will pass over the pins, without receiving any injury from 95 them. As soon as the paper has passed the pins they recover their vertical position, preparatory to being used as a means of presenting another sheet of paper in its proper position to the first pair of folding 100 rollers. As the folded sheet passes between the latter, it is directed by a system of tapes or bands (so fully described in my former 105 patent, as to need no explanation here) toward the second pair of folding rollers, the folded sheet being arrested by the stop z (Fig. 4), against which the folded edge bears, and by which it is presented in its proper position to receive the second fold. During this part of the operation, that is 110 from the time the sheet is leaving the first pair of folding rollers until it is about to receive the second fold, there are two points at which the sheet may be so operated upon as to become defective. One point is that 115 where the folded edge of the sheet, after leaving the first pair of folding rollers, comes in contact with the tapes or bands, and, being bent by the latter, is apt, as the sheet passes on, to continue the bend and 120 curl up, following the direction of the roller L'. The other point where a defect might originate, supposing the first point to have 125

been passed in safety, is where the edge comes in contact with the stop z , when that edge, owing to the warping or buckling of the paper, is not quite straight. The means 5 of preventing any defects at these two points, form an especial feature in my present improvements.

It has been already observed, that the rods 1, 2, and 3, pass into grooves 7, cut into 10 the roller L' , that the rods terminate at or about a line drawn perpendicularly through the center of that roller, and that the under side of the rod is level or thereabout with the underside of the rollers. Now, on referring to Fig. 6, and noting the position of 15 these rods, it will be seen, that it will be impossible for the folded edge of the sheet, as it passes from the rollers, to turn up and follow the direction of the roller L' , as the rods present a bar to prevent this, and serve to guide the sheet safely past this dangerous point.

Occasionally, through the warping or buckling of the paper, the first fold will present an edge slightly rounded. Should the 25 stopping bar Z be straight, and a rounded edge of a sheet be brought in contact with it, there would be no certainty of that sheet being presented in its proper position to receive the second fold. In other words, as 30 the rounded edge of the sheet is forced against the stop (still supposing the latter to be straight), the sheet has an opportunity to adjust itself at an angle to the stop, or at 35 an angle to the second pair of folding rollers. Consequently, the second fold accomplished by these rollers, would not be at right angles to the first fold, and should this second fold be even but a trifle out of its 40 proper angle, the third fold would be still further out of truth, and the same with the last fold. The folded sheet would be thus so imperfect, as to be unfit for use. Hence 45 the importance of forming the inner face of the stop Z of a curved or angular form, so that the ends of the folded edge only can come in contact with it, in which case any intermediate rounding of the edge between the two ends can in no way affect the assumption by the folded sheet of a proper 50 position against the stop, for receiving the second fold.

The second fold is accomplished by the blade on the end of the arm Q , creasing the 55 sheet and forcing it between the rollers P and P' ; the third fold by a blade on the arm V forcing the paper between the rollers R and R' ; and the fourth and last fold by a blade on the arm W forcing the paper between the 60 rollers V and V' . The fourth fold, however, is not always required, in which case the bands for directing the sheet to these rollers are thrown off, and the folded sheet falls into the trough O , between the

sliding board O' and the reciprocating plunger C . In the machine, as shown in Figs. 1 and 2, the last pair of rollers are not supposed to be in use.

At the time the thrice folded sheet falls into the trough, the reciprocating plunger C (Fig. 2) has, through the action of the eccentric, been moved to the limit of its backward movement. As soon as the sheet has been fairly deposited in the trough, however, the plunger C moves forward and pushes it against a body of previously folded sheets, which bear against the sliding board O' .

The adjustable plate 9 and the tongue 10 have been previously alluded to. This plate and tongue, as will be seen in Fig. 2, coincide with each other. Now the plunger C is so arranged and regulated as to push the folded sheet a short distance past the tongue and plate. The upper corner of the folded sheet will consequently be pressed down, as seen in Fig. 9, the top of the adjustable plate 8 of the plunger being the point where the bend at the corner of the sheet will take place. At the same time, the tongue 10 will be forced down by the advancing sheet. After the corner of the sheet has passed the lower edge of the plate 9, and after the edge of the sheet has passed the point of the depressed tongue 10, and the lower corner over 95 an angular strip 17 in the corner of the trough, the upper corner of the sheet will recoil or spring back, recovering as it were from the bend. At the same time the plunger will recede, the tongue 10 will be elevated and, together with the strip 17, prevent the return of the lower end of the sheet, while the upper end is prevented from returning by the plate 9. Thus the folded sheet becomes one of the body previously 100 folded and confined between the sliding board O' , on one side, and the tongue 10, strip 17 and plate 9 on the other side, while the plunger recedes, preparatory to forcing another folded sheet forward and adding it to the body thus collected in the trough. 110

As every folded sheet in succession is added, the sliding board O' moves a short distance along the trough, and this movement is retarded by the springs 4 (Fig. 1), one of which, as before remarked, bears against one of the strips 5, situated on each side of the trough. This retarded motion causes the plunger to pack and compress the folded sheets into a compact mass. In order that they may be compressed to an equal density throughout, it is necessary that the friction of the board O' against the side of the trough should be removed, as the mass of folded sheets accumulates, inasmuch as the weight of the folded sheets and their constant increase of bulk, add to the friction. In order to diminish the friction of the sliding board, the strips 5 on the outside of the box are 115 120 125

made of the wedge shape or angular form already described, so that, as the board approaches the end of the trough, the springs pass over an inclined plane, and, consequently, the rigidity of their bearing against the strips, and of course their friction decreases. A uniform compactness of the whole mass of sheets contained in the trough is thus obtained.

10 It is desirable that the attendant should be made aware, or should be able to readily ascertain without counting, the number of perfectly folded sheets contained within the trough, so that they may be removed in 15 masses containing a specific number, thereby facilitating the subsequent operations, through which the sheets must pass preparatory to being bound. An indicating apparatus, connected with or driven by any of 20 the regularly moving parts of the machine, would not perform this duty with precision, inasmuch as some of the sheets, which are found to be imperfect after they have been adjusted to the register pins, are, by means 25 of a device described in my former patent, directed away from the trough, as they are receiving their last fold.

The spindle 11, to which the tongue 10 is attached, or of which it forms a part, projects beyond the trough, and is furnished with a projection, which may be connected to any suitable indicating and alarm apparatus. As the spindle is turned backward and forward once only on the accession 35 of every newly folded sheet to the mass contained in the trough, and as these sheets are all perfectly folded, it is evident that an indicator, operated by this spindle, must point out accurately the number of sheets 40 contained in the trough.

When the last pair of folding rollers V and V' are used, so as to complete a fourth fold of the sheet, it is evident that as they are in a line or thereabout with the trough, 45 the folded sheets would fall into the latter in such a position, that the packing arrangement, above described, could not be used. This difficulty is overcome by the bracket 14 and its curved wires 15 and 16, represented in Fig. 10. These wires are placed 50 directly under the last pair of rollers, and are so bent and situated, as regards the trough, that, as the sheet passes from between the rollers, it comes in contact with 55 the wires, the peculiar bend of which so turns the sheet around, that, instead of falling with its edge in a line with the trough, which, but for this provision it would do, it falls with its edge across the trough, precisely 60 in the same manner as the sheets falling from the third pair of folding rollers. When the fourth pair of folding rollers are used, the plunger C should be so adjusted on the rod, by which it is connected to the

vibrating arm 7, as to be nearer to the wires 65 15 and 16 than it is represented to be in Fig. 2.

As sheets of various sizes are folded in the machine, it is evident that the plate 9, by which the upper corner of the folded 70 sheet is bent over the plate 8 of the plunger C, as well as the plate 8 itself, should be made adjustable, so as to be readily adapted to sheets of different sizes. It will be observed, on reference to Fig. 8, that both of 75 these plates have slots, through which the screws, which secure them to their proper positions pass, so that they can be readily adjusted to suit the different sizes of the sheets.

Having now described the construction and operation of my improvements, I wish it to be distinctly understood that I do not desire to confine myself to the precise construction of the devices herein described, as 85 several modifications of or equivalents to the same might be substituted without departing from the main features of the invention; but

I claim and desire to secure by Letters Patent,

1. The register pins e and e', so constructed and so attached to a paper folding machine, that they shall retain a position proper for the adjustment of the sheet, and yield by the movement of the latter.

2. Adjusting one of the register pins e' laterally and longitudinally, independently of the other pin, by means of the slides n' and n² or their equivalents.

3. Adjusting both pins simultaneously, both laterally and longitudinally, by the frames X and Y or their equivalents, the frame X being adjustable in one direction on the frame Y, and the latter, together with the frame X, being adjustable in another direction on the frame of the machine, or any attachment thereto.

4. Any convenient number of rods 1, 2 and 3, terminating at one of the folding rollers, the ends of the rods passing into 110 grooves in the said rollers as and for the purpose specified.

5. The adjustable stop Z, with its inner edge of a curved or angular form, or otherwise so constructed that the end of the 115 folded edge only of the sheet shall be in contact with the said stop, for the purpose specified.

6. The plunger C, with its adjustable plate 8, in combination with the adjustable plate 120 9, the said plates being arranged substantially as and for the purpose herein set forth.

7. The curved wires 15 and 16 or their equivalents, attached to the machine in any 125 convenient manner, situated under the folding apparatus, and adjacent to the trough, for the purpose specified.

8. The combination of an alarm or indicating apparatus with a paper folding machine, when the said indicator is operated by a sheet folded by the machine.
- 5 9. Causing the sliding board O' to move along the trough with a diminution of friction as the folded sheets accumulate, by means of the springs 4, attached to the said board, and arranged to bear against the 10 wedge-formed or inclined strips 5, substan-

tially as herein set forth and for the purpose specified.

In testimony whereof, I have signed my name to this specification in the presence of two subscribing witnesses.
